WASHING-MACHINE.

1,121,451.

Specification of Letters Patent.

Patented Dec. 15, 1914.

Application filed November 6, 1913. Serial No. 799,512.

To all whom it may concern:

Be it known that we, ANDREW D. BAIRD and EFFIE J. FAVOR, citizens of the United States, and residents of Medford, in the county of Middlesex and State of Massachusetts, have made certain new and useful Improvements in Washing-Machines, of which the following is a specification.

This invention relates to washing machines, and more particularly to portable washing machines.

One of the principal objects of the invention is to provide a portable clothes carrying drum and means for quickly and easily attaching it to a stationary tub, and for rotating the drum when in position.

Another object of the invention is to provide a pair of brackets or hangers adapted to be secured to the walls of a stationary tub, to support a rotary clothes carrying drum, the brackets also provided with means for rotating the drum in supported position.

A further object of the invention is to provide a device of the class described which will be simple, durable, efficient in operation and comparatively inexpensive to manufacture.

With these and other objects in view, which will become apparent as the description proceeds, the invention resides in the construction, combination and arrangement of parts hereinafter more fully described and claimed, and illustrated in the accompanying drawing, in which like characters of reference indicate like parts throughout the several figures, of which,

Figure 1 represents a vertical longitudinal sectional view taken through a stationary wash tub, showing the invention in place thereon. Fig. 2 represents an end elevational view looking from the right of Fig. 1, and Fig. 3 represents a vertical transverse sectional view taken on the plane indicated 45 by the line 3-3 of Fig. 1.

Referring more particularly to the drawing, the invention is illustrated as applied to a stationary tub comprising a bottom 5, end walls 6, side walls 7 and supports 8, for maintaining the tub in raised position over a floor or other base. To the end walls 6 of the tub are removably attached substantially inverted U-shaped hangers 9 and 10, comprising back portions lying against the upper edges of the end walls, and inner and outer legs lying against the inner and outer

faces respectively of the end walls, and the inner leg of hanger 9 is substantially longer than the outer leg thereof and depends to about the center of the adjacent end wall. 60 A thumb bolt 4 extends through the outer leg of hanger 9 for removably securing said hanger to its end wall.

The back portion of hanger 10 is extended to both sides of the hanger along the top 65 edge of the adjacent end wall and a pair of depending ears 11 are formed at the ends of said back portion and carry thumb bolts 12 by which the hanger may be detachably secured to the tub, a third thumb bolt 13 being provided in the outer leg 14 of the hanger about midway thereof, to assist thumb nuts 12 in positioning the hanger. The lower end of leg 14 is provided with a right angular horizontal shelf 15 adapted to 75 carry a motor 16.

Inner leg 17 of bracket 10 depends within the tub and is of a length corresponding to the inner leg of hanger 9, and leg 17 is provided at its lower end with an opening to receive a bearing pin 18 carried by a hexagonal block 19 which forms one end of a drum 20, the other end of which is formed of a similar hexagonal block 21 supported by means of a bearing pin 22 in the lower end 85 of a recess 23 cut in the inner leg of hanger 9 in the same horizontal plane as the opening in the leg 17 so that the drum may be supported horizontally and rotatably within the tub. 90

The hexagonal blocks are connected by longitudinally disposed spaced bars 24 secured at their ends to said blocks. One face of the drum thus formed is provided with transverse bars 25 connecting the bars forming that face, said face or wall of the drum being hinged as at 26 and provided with a hook 27 adapted to engage an eye in one of the bars 24 so that a closure is provided for the drum, whereby goods to be washed may 100 be placed in or removed from the drum.

The bearing pin 18 is of such a length as to space block 19 from the adjacent leg 17, and on said pin between the block and leg is secured a large sprocket wheel 28 connected 105 by means of a chain 29 with a smaller sprocket wheel 30 secured at the inner end of a shaft 31 journaled horizontally and transversely of the back portion of hanger 10, the outer end of shaft 31 carrying a 110 pulley 32 connected by means of a belt 33 with a driving pulley 34 to the shaft of the

motor 16, whereby the drum may be rotated within the washing fluid contained in the tub, it being noted that by reason of the hexagonal or many sided construction of the drum, that the clothes will be thoroughly shaken up and agitated thus becoming thoroughly saturated with the washing fluid.

By this construction it is evident that the washing drum may be easily cleaned and may when not in use, either be left in the tub, where it is inconspicuous and out of the way, or it may be removed, together with the hangers, to be stored in a suitable place until needed.

Although we have shown the driving means between the shaft 31 and the drum as comprising sprockets and a chain, it is evident that the driving means might comprise suitably arranged cog wheels, or a belt and pulleys, or other transmission means. It will also be understood that although the drum has been described and shown as being six sided, the exact number and arrangement of its sides may be altered without departing from the spirit of the invention, and we

may desire to make such changes in the construction, combination and arrangement of the parts of the invention as do not depart from the spirit thereof, and the scope of the appended claim.

We claim:—

A washing machine comprising a tub, a drum, means for removably positioning said drum within the tub, said means including a hanger having a back portion spanning one wall of the tub, legs depending from the back portion within and without the tub, said legs being of substantially equal length, the outer leg provided with clamping means removed considerably from the back portion, said back portion being extended to either side of the common plane of the legs, and provided with spaced ears depending without the tub, and clamping means carried by the ears.

ANDREW D. BAIRD.
EFFIE J. FAVOR.
